UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

BOX-FILLING MACHINE.

Application filed November 17, 1921. Serial No. 515,815.

To all whom it may concern:

Be it known that I, MICHAEL PARIDON, a citizen of the United States, and resident of Barberton, in the county of Summit and State of Ohio, have invented certain new and useful Improvements in Box-Filling Machines, of which the following is a specification.

This invention relates to box filling machines, having reference, more particularly, to machines employing a trough-like hopper for supplying matches, or other splint-form articles, to progressing trays on the upper run of a tray-and-shuck conveyer, such, for example, as disclosed in Letters Patent of the United States No. 1,300,762, dated April 15, 1919, and No. 1,360,438, dated November 30, 1920.

In the machine of the first-named patent the box-trays are singly supplied with matches, while in the machine of the later patent plural trays are simultaneously supplied with measured quantities of matches from the hopper.

The present invention concerns improved means for accurately and rapidly measuring and supplying matches to the box trays, such means being especially, though not exclusively, designed for use in connection with a machine of the plural tray supply type above referred to.

According to my invention I provide adjacent the delivery portion of the hopper a longitudinally-extending measuring chamber into which the matches are progressively delivered, said chamber having associated therewith means operable to check the delivery of the matches to the chamber at predetermined intervals and also to permit the discharge of the contents of the chamber to underlying box trays.

The invention also includes means whereby the contents of the chamber are divided into a plurality of measured quantities, and such quantities then deposited simultaneously into a plurality of underlying box trays.

The invention also comprises various novel features of construction and combinations of parts which will be hereinafter described and claimed.

Figure 1 is a side elevation of a portion of a box-filling machine embodying my invention; the partitioning head being shown in down position.

Fig. 2 is a transverse vertical section of the machine, as on the line 2—2 of Fig. 1.

Fig. 3 is a perspective view of the match partitioning head.

Fig. 4 is a sectional perspective view of the portion of the trough included in the measuring chamber, showing the bottom slide and the throat structure.

Fig. 5 is a transverse vertical section, enlarged, of the measuring chamber, and ad- juncts.

Fig. 6 is a longitudinal vertical section, as on the line 6—6 of Fig. 5.

Fig. 7 is a similar view, showing the head in raised position preparatory to its descent.

Fig. 8 is a similar view, showing the head in down position, the bottom slide retracted, and the matches deposited in the underlying trays.

Referring to the drawings, 10 designates an elongated hopper into which matches are delivered from a suitable source of supply so as to lie in approximate parallelism within and transversely of the hopper. This hopper, in the form illustrated, comprises an inclined bottom 11 having parallel sides which are spaced apart a distance slightly greater than the length of a match. The sides of the hopper are horizontally extended at its lower end, as at 12, and these extensions, together with the adjacent part of the bottom of the hopper, overhang a horizontal bed or table 13 upon which the upper run of the endless conveyer 14 containing the box-trays 15 is supported and guided.

The hopper is provided with a suitably-disposed slide 16 which is mounted on a guide standard 17 on the table to permit longitudinal vibration of the hopper in order to settle the matches therein and assist them in their descent to the delivery end of the hopper.

The hopper is also provided with suitably-disposed depending lugs 18 which embrace an eccentric 19 carried by a shaft 20 driven in any suitable manner to effect the rapid bodily vibration of the hopper.

A resilient guard structure 21 is arranged within the lower portion of the hopper to provide therewith a tapering of contracted throat through which pass the match contents of the hopper. The structure preferably comprises an inclined metal strip which is secured at its upper end to the sides of the hopper, as at 22. The lower portion of the strip is spaced above the delivery end of the

105 strip is spaced above the delivery end of the 110

105 strip is spaced above the delivery end of the 110

hopper bottom a distance approximately equal to the depth of a box tray, and is extended horizontally, as at 23, preferably a distance sufficient to overhang two underlying box trays in the conveyer 14, as hereinafter explained. The horizontal extension is longitudinally slotted, as at 24, and its free end is bent downward to provide an end wall 25 which depends in proximity to the path of a longitudinally reciprocative slide plate 26. A U-bracket 27, affixed to the extension 23, is provided at its upper ends with laterally-projecting lugs which overlie the adjacent side walls of the hopper and thus limit the downward position of the extension in relation to the slide plate. This plate, which is fitted to horizontal guide ways 28 in the inner sides of the hopper, constitutes, in effect, a reciprocative extension for the delivery end of the hopper bottom, and is movable in a path directly above the walls of the conveyer so as to afford a temporary support for an accumulation of matches. The plate extends beneath the hopper bottom and is provided with a laterally-extending head 29 which is slidably mounted in a guide structure 30 on the table. The under side of the head 29 is jointed to the upper arm of a rock-lever 31 which is pivoted to a bracket 32 under the table, the lower arm of the lever being provided with a roll 33 engaged with the groove of a cam 34 on a driven shaft 35 of the machine. The contour of the cam groove is such that at predetermined intervals the lever is oscillated in order to reciprocate the slide 26 in relation to the delivery end of the hopper bottom. The upper surface of the slide is longitudinally channelled, as at 36, for a purpose hereinafter explained.

The extension 23, its end wall 25 and the slide 26, together with the adjacent sides of the hopper, constitute a closed measuring chamber into which the matches are progressively delivered when they pass beyond the bottom of the hopper.

A vertically reciprocative head 37, which overhangs the hopper in a plane above the measuring chamber, is provided in the present instance with two spaced-apart depending blades 38, 39 which in the reciprocation of the head are movable through the slot of the extension 23 and into and from the matches supported on the slide 26 so as to partition the chamber and divide such matches into two separate quantities each sufficient to supply a box-tray. In the present instance the head is formed on or connected to a vertically-reciprocative bar 40 which depends through a guide in the table and is jointed at its lower end to one arm of a rock-lever 41 which is pivoted on a depending bracket 42 beneath the table. The other arm of the lever is provided with a roll 43

engaged with the groove of a cam 44 on the shaft 35; the contour of the groove being such that at predetermined intervals the arm and perforce the bar, together with the head and its blades, are vertically reciprocated.

Assuming the bottom of the measuring chamber be closed, and the head be in raised position, as shown in Fig. 7, the matches will be delivered directly by the vibrating hopper into the chamber and the latter will be filled with matches. If now the head be lowered the blades 38, 39 will enter into the mass of matches in the chamber and partition them into two measured quantities, the blade 39 at the same time serving as a gate or cut-off to check the passage of the matches from the delivery portion of the hopper, as seen in Fig. 6. This done, if the slide 26 be retracted, as seen in Fig. 8, the two measured quantities of matches will fall from the chamber into the two underlying box trays in the conveyer. Thereupon if the slide be again projected beneath the measuring chamber and the partitioning blades be raised, matches will again enter the measuring chamber from the body of the hopper preparatory to a repetition of the measuring and tray filling operations just described.

The depression or channel 36 in the top of the slide 26 is of less width than the length of a match in order that the matches shall bridge the channel; and the lower edges of the blades are of less width than the channel so that the blades, entering the channel, will descend below the matches. By this construction the blades in their descent displace the matches laterally and thus obviate any liability of impinging against and crushing the lowermost matches.

The conveyer is intermittently actuated to position successive pairs of box trays directly beneath the measuring chamber, preparatory to the withdrawal of the slide 26. In the present instance a conveyer of the character illustrated in Patent No. 1,360,438 is employed, said conveyer being constructed to support trays and shucks in endwise relation to each other, so that the filled trays can be inserted into their complementary shucks and covers during the progress of the conveyer. The conveyer passes about sprocket wheels arranged at or adjacent the respective ends of the table, one of which wheels is shown at 45. The wheel is mounted on a transverse shaft 46 having its bearings in brackets 47 beneath the table. This shaft bears a pin wheel 48 with the successive pins of which engages a worm cam 49 on a shaft 50 provided with a gear 51 meshing with an idler gear 52, which in turn meshes with a gear 53 on the shaft 35. The contour of the worm cam 49 is such that in each rotation thereof the pin wheel is actuated to

effect the intermittent advancement of the conveyer and position a pair of box trays beneath the measuring chamber.

While I have herein shown and described my invention in a form designed to measure off simultaneously two quantities of matches for delivery to two trays, it is to be understood that a less or greater number of quantities may be measured off and delivered to a correspondingly less or increased number of box trays; such trays in any case being advanced in proper sequence to receive the measured quantities of matches. It is also to be understood that the mechanism herein disclosed may be modified in various respects without departing from the principle of the invention and the scope of the appended claims.

I claim—

1. In a match-box filling machine, a hopper having a longitudinally extending delivery portion, a measuring chamber extending longitudinally from and forming a continuation of such delivery portion, said chamber including a movable bottom member, a gate member operable to control communication between the delivery portion of the hopper and the measuring chamber, means for intermittently feeding a succession of trays beneath and past the bottom of the measuring chamber, and means for operating the said bottom and gate members at predetermined intervals.

2. In a match-box filling machine, a hopper having a longitudinally extending delivery portion, a measuring chamber extending longitudinally from and forming a continuation of such delivery portion, said chamber including a movable bottom member, an element comprising a plurality of spaced apart partitioning members movable into and from the contents of the measuring chamber, one of said partitioning members constituting a gate operable to control communication between the delivery portion of the hopper and the measuring chamber, means for intermittently feeding a succession of trays beneath and past the bottom of the measuring chamber, and means for operating the said bottom member and the partitioning element at predetermined intervals.

3. In a match-box filling machine, a horizontally-disposed measuring chamber including a movable bottom member, means for supplying matches to said chamber when the bottom thereof is closed by said member, an element comprising a plurality of spaced apart partitioning members movable into and from the contents of the chamber, means for intermittently feeding a succession of trays beneath and past the bottom of the measuring chamber, and means for

operating the said bottom member and the partitioning element at predetermined intervals.

4. In a match-box filling machine, a horizontally-disposed measuring chamber including a movable bottom member, means for supplying matches to the said chamber when the bottom thereof is closed by said member, means for partitioning the contents of the chamber into a plurality of measured quantities, means for intermittently feeding a succession of trays beneath and past the bottom of the measuring chamber, and means for operating the said bottom member and the partitioning element at predetermined intervals, whereby measured quantities of matches are delivered to a corresponding number of underlying trays.

5. In a match-box filling machine, a horizontally-disposed measuring chamber including a horizontally reciprocative bottom member, means for supplying matches to the said chamber when the bottom thereof is closed by said member, a vertically reciprocative head overlying the said chamber, a plurality of spaced apart partitioning blades depending from said head, means for feeding a succession of trays beneath and past the bottom of the measuring chamber, means for reciprocating said head to move its blades into and from the chamber, and means for reciprocating said bottom member to open and close the bottom of the chamber, said bottom being opened when the blades are positioned within the measuring chamber.

6. In a match-box filling machine, a horizontally-disposed measuring chamber including a horizontally reciprocative bottom member and a top spaced from said bottom member, means for supplying matches to said chamber when the bottom thereof is closed by said member, an element comprising a plurality of spaced-apart partitioning blades vertically movable into and from the contents of the chamber, the top of said chamber being slotted for the passage of the blades, means for intermittently feeding a succession of trays beneath and past the bottom of the measuring chamber, and means for operating said bottom member and the partitioning element at predetermined intervals.

7. In a match-box filling machine, an elongated hopper having an inclined bottom, an inclined member located within the delivery portion of the hopper and providing therewith a contracted throat portion, the free end of said member being extended horizontally beyond the delivery end of the hopper bottom and constituting the top of a measuring chamber, a movable bottom for said chamber, an element comprising a plu-

rality of spaced-apart partitioning members movable into and from the measuring chamber, one of said partitioning members constituting a gate operable to control communication between the delivery portion of the hopper and the measuring chamber, means for intermittently feeding a succession of trays beneath and past the bottom of the measuring chamber, and means for operating the said bottom member and the partitioning element at predetermined intervals.

8. In a box filling machine, a horizontally-disposed measuring chamber, including a movable bottom member having a depression in its upper supporting surface, means for supplying matches to said chamber when the bottom thereof is closed by said member, a gate vertically reciprocative in said chamber and into and from the depression in the bottom member, means for intermittently feeding a succession of trays beneath and past the bottom member of the measuring chamber, and means for operating the said

bottom and gate members at predetermined intervals.

9. In a box filling machine, a horizontally-disposed measuring chamber, including a movable bottom member having in its upper surface a longitudinal depression of less width than the length of a match, means for supplying matches to said chamber when the bottom thereof is closed by said member, a vertically reciprocative element comprising a plurality of spaced-apart partitioning members movable into and from the contents of the measuring chamber and into and from the depression of the bottom member, means for intermittently feeding a succession of trays beneath and past the bottom of the measuring chamber, and means for operating the said bottom member and the partitioning element at predetermined intervals.

Signed at Barberton, in the county of Summit and State of Ohio this 14 day of November A. D. 1921.

MICHAEL PARIDON.
